CLAIM

The ornamental design for a supply spool for a fishing line, as shown and described.

DESCRIPTION

FIG. 1 is a left side, top and front perspective view of a supply spool for a fishing line showing our new design; FIGS. 2 and 3 are, respectively, top and bottom plan view thereof;

FIGS. 4 is a front elevational view thereof, the rear elevational view being a mirror image, and the side elevational view being identical to FIG. 4; and

FIG. 5 is a vertical sectional view taken in the direction of the arrow on the lines 5—5 of FIG. 3.
